UNITED STATES PATENT OFFICE

RAYMOND M. ANDERSON, OF CHICAGO, ILLINOIS, ASSIGNOR TO STROMBERG MOTOR DEVICES COMPANY, OF CHICAGO, ILLINOIS, A CORPORATION OF ILLINOIS.

CARBURETER.

1,179,386.

Specification of Letters Patent. Patented Apr. 18, 1916.

Application filed May 27, 1912. Serial No. 699,864.

To all whom it may concern:

Be it known that I, RAYMOND M. ANDERSON, a citizen of the United States, and resident of Chicago, in the county of Cook and State of Illinois, have invented a certain new and useful Improvement in Carbureters, of which the following is a full, clear, concise, and exact description, reference being had to the accompanying drawing, forming a part of this specification.

My invention relates to carbureters for use in association with internal combustion engines and it is concerned with improved means for regulating the fuel supply in order that the proper proportion between the fuel and the air is maintained under the different running conditions.

My carbureter is of that type in which a constant level is maintained by the use of an auxiliary chamber, such as a float chamber, and it is my idea to vary the pressure on the top of the liquid fuel, such as gasoline, in the float chamber by means of an arrangement responding to the suction of the engine with which the carbureter is associated. It is toward the means for varying the pressure on the top of the fuel in the float chamber that my invention is directed. The chamber above the fuel in the float chamber is connected by means of a passageway with the carbureting chamber so that it is subject to the pressure therein. This passageway, however, is controlled by means of a valve, and the extent to which the pressure in the carbureting chamber is effective in the float chamber is determined by the position of this valve. Furthermore, viewing my invention in this more specific aspect, this valve is operated with a secondary or auxiliary air valve and, in the particular form herein shown and described, this air valve is carried with a special piston which is arranged to be subject to the pressure in the carbureting chamber. The piston and auxiliary valve arrangement is easily operative and is substantially the same as that shown in the co-pending application of John S. Goldberg, Serial No. 699,838, filed May 27, 1912. The movement of the auxiliary air valve is imparted to the valve controlling a passageway to the top of the float chamber and it will be seen that at the various speeds there will be corresponding variations in the supply of fuel, these variations being accompanied by

variations in the supply of air, as will be pointed out.

My invention is illustrated in the accompanying drawing which is a view partly in elevation and partly in longitudinal axial section.

The casing is illustrated at 5 and it will be seen that it provides the carbureting chamber 6 to which the primary air passage in the form of a Venturi tube 7 leads. The outlet for the carbureting chamber 6 is controlled by a throttle valve 8 and is surrounded by a flange 9 by means of which the device may be secured to the manifold of the engine. The primary air inlet passageway 8' connects with the lower end of the Venturi tube and this air inlet is supplemented by an air horn 9' which is secured in place by means of a nut 10 screwing into a stud 11 extending downwardly from a bridge 12 spanning the air inlet passageway 8. This air horn is provided with a valve 13 mounted upon a shaft extending outside the horn and provided therewith an operating lever 15. A spring 70 pressed plunger 16, which is adapted to rest in grooves in the periphery of the hub of the operating lever holds the valve 13 in either its open or closed position. The air horn 9' may be connected with a warm air inlet and the warm air going in in this way may be diluted by cold air entering through the side passages 17 which are controlled by an annular valve 18.

The bridge 12 is in the form of a tube 90 and forms a fuel passageway. The fuel used is in liquid form, such as gasoline, and it is introduced into the carbureter through a float chamber 19. The float chamber is provided with an entry coupling 20 which is connected with the source of fuel supply.

The float chamber is provided with a float 20' which, through the medium of levers 19', operates a valve 18' controlling the gasoline inlet passageway 17'. A fuel emitting nozzle 21 is supported on the top of the bridge 12 and is located axially in the Venturi tube, ending in substantially the most contracted portion thereof. The Venturi tube may be surrounded by a water jacket 95 100 105 110 115 122.

At one side of the carbureting chamber 6 there is provided the auxiliary supply chamber 23 into which a passageway 24 leads. This passageway is connected, by means of

a small tube 25, lying in the passageway through the bridge 12, with the float chamber over the level of the liquid therein, as indicated by the line *x*. Except for the connection with the tube 25, the passageway 24 is connected by means of a sleeve 24' and it will be understood that the passageway 24 and tube 25 thus connect the chamber over the fuel in the float chamber with the carbureting chamber.

Below the auxiliary supply chamber 23, there is a valve chamber 26 and below the valve chamber there is a piston chamber 27. A piston 28 is mounted to reciprocate vertically in the chamber 27 and it carries a tubular shaft 29 which extends upwardly and which is provided with a reduced portion 30 mounted to reciprocate in a boss 31 in the upper wall of the chamber 23. A spring 32 is disposed inside the tubular shaft 29 and between a shoulder 33 therein and the base of the piston chamber 27. The bore of the shaft 29 is exposed to the auxiliary supply chamber 23 and thus to the carbureting chamber 6 through the side opening 34, and it will be seen that the pressure is accessible to the underside of the piston 28 in this way. The upper side of the piston is open to atmosphere. An annular valve 35 is disposed in the valve chamber 26 and is held in place, so that it may be given angular movement, by means of the plate 36. This valve has a central opening for the passage of the shaft 29 and is in the form of a ring 35 in which the automatic valve 37, secured to the shaft 29, may operate.

The valve casing 26 is provided with one or more side inlets 38, 38, indicated in dotted lines, and the valve 35 is provided with one or more openings 39. When the valve 35 is in the position shown in the drawing, the openings 38 are closed, but it will be seen that the valve may be given angular movement to give the openings any desired effective size.

The normal position of the valve 37 is its uppermost position, as shown in the drawing, and in this position it cuts off the auxiliary supply chamber from the atmosphere openings 38. When the suction created in the carbureting chamber has reached a predetermined point, however, it overcomes the tension of the spring 32 and, playing on the under surface of the piston 28, draws the piston down and with it the valve 37 so that more or less of the openings 38 may be brought into operative connection with the auxiliary supply chamber.

Mounted in an opening in the top of the auxiliary supply chamber 23 is a bushing 43 and a lever 44 is mounted upon a pivot 45 carried by this bushing. The end of this lever is bifurcated at 46 so that it may embrace a collar 47 adjustably screw-threaded upon the end of the rod 30. This sleeve may

be held in any adjusted position by means of spring pressed balls 48, 48 which rest in peripheral grooves in the rod. The lever 44 engages with the valve carrier 49 which extends into the chamber 23 and is there provided with a needle valve 50 disposed in axial alinement with an outlet in the passageway 24 so that it may enter said outlet and so that its vertical movement will determine the effective area of said outlet. The needle valve 50 is more or less loosely mounted, under the tension of the spring 51, so that it may seat itself properly at the proper time.

The top of the float chamber 19 is connected with the atmosphere through a restricted opening 52. When the passageway 24 is in open communication with the pressure in the carbureting chamber 6, any suction in the carbureting chamber will subtract from the effect of the atmosphere on the surface of the fuel in the float chamber. And the amount subtracted in this way may be regulated by positioning the valve 50. The taper of this valve is such that the proper variation in the subtracting effect is had in order that a leaner mixture may be obtained for the higher speeds. When the automatic auxiliary air valve is closed, the passageway 24 is restricted only to such an extent that the atmosphere may move only the proper amount of fuel for low speeds through the nozzle 21. As the suction of the engine increases, however, the auxiliary air valve 37 is drawn down to admit more air and the valve 50 is also drawn down so that the subtracting effect of the suction of the carbureting chamber 6 will be cut off to a considerable extent. This allows the atmosphere to play more freely and more fuel is moved through the nozzle 21. The proper amount of auxiliary air may be adjusted in the first place by manipulating the manual valve and thereafter the proper relative amount thereof will be determined by the position of the automatic valve.

I claim as new and desire to secure by Letters Patent:

1. In a carbureter, a carbureting chamber, a fuel inlet nozzle therefor, an air inlet therefor, a fuel reservoir connected with said fuel inlet, a restricted air supply to said reservoir, a passageway leading from the top of the reservoir to the carbureting chamber, an auxiliary air inlet, a valve responsive to the pressure in said carbureting chamber controlling said auxiliary air inlet, and a valve for varying the size of said passageway and mechanically connected with said auxiliary air valve.

2. In a carbureter, a carbureting chamber, a fuel nozzle therefor, an air inlet therefor, a float chamber connected with said fuel nozzle, a restricted air supply to said reservoir, a passageway connecting said car-

bureting chamber with the top of said float chamber, a secondary air inlet, an automatic valve for said secondary inlet, and means operated with said secondary air inlet valve 5 for varying the size of said passageway.

3. In a carbureter, a carbureting chamber, a fuel inlet nozzle therefor, an air inlet therefor, a fuel reservoir connected with said fuel inlet, a passageway leading from 10 the top of the reservoir to the carbureting chamber, an auxiliary air inlet, a valve controlling said auxiliary air inlet, a valve controlling said passageway and mechanically connected with said auxiliary air valve, and 15 a piston responsive to the suction of the engine for moving said valve.

4. In a carbureter, a carbureting chamber, a valve chamber with an air inlet associated therewith, a piston chamber, a piston 20 in said piston chamber, an air valve in said valve chamber, a manually operated valve controlling said air inlet, a fuel inlet, a reservoir supplying said fuel inlet, a passage between said reservoir over the liquid 25 level and said carbureting chamber, a valve in said passage, and mechanical connection between said last-named valve, said air valve and said piston.

5. In a carbureter, a carbureting cham-

ber, primary air and fuel inlet means, a 30 throttle valve controlling the outlet, a float chamber connected with said nozzle, a passage between the top of said float chamber and said carbureting chamber, a vertical cylindrical valve chamber with side inlets, a 35 tubular valve within said valve chamber operated manually to vary the effective size of said side outlets, a piston valve in said tubular valve, a piston chamber below said valve chamber, a piston in said piston chamber, a hollow shaft connecting said pistons, said hollow shaft passing through the carbureter chamber and having its bore exposed thereto, the underside of the piston being thus exposed to the pressure in the 40 carbureting chamber and the other side of the piston being exposed to the atmosphere, said hollow shaft extending beyond the casting, a loosely mounted needle valve for the 45 passage, a carrier for said valve, and a lever engaging said carrier and adapted to be engaged by a part on said shaft.

In witness whereof, I hereunto subscribe my name this 24th day of May, A. D., 1912.

RAYMOND M. ANDERSON.
